Application filed November 2, 1889. Serial No. 329,084. Term of patent 3½ years.

To all whom it may concern:

Be it known that I, JOHN HENKEL, of Hoboken, in the county of Hudson and State of New Jersey, have invented and produced a new and original Design for Chatelaine-Bags, of which the following is a specification, the accompanying drawing, forming a part thereof, representing a side elevation of my design.

The design consists of a chatelaine-bag having upon its side face a series of lines *a*, extending virtually from end to end and so

drawn as to impart to the said side the appearance of a series of overlapping cape-like figures.

I claim—
